UNITED STATES PATENT OFFICE.

WILLIAM A. HARVEY, OF SCRANTON, PENNSYLVANIA.

ELECTRICAL APPLIANCE.

J 339,847.

Specification of Letters Patent. Patented May 11, 1920.

Application filed March 5, 1915. Serial No. 226,524.

To all whom it may concern:

Be it known that I, WILLIAM A. HARVEY, a citizen of the United States, and resident of Scranton, in the county of Lackawanna and State of Pennsylvania, have invented 5 certain new and useful Improvements in Electrical Appliances, of which the following is a specification.

The present invention relates in general 10 to electrical appliances and particularly to an adapter for that class of electrical fittings known to the trade as condulets, unilets, taplets, etc., such fittings being commonly used in connection with metal conduit systems of electric wiring, for the purpose of 15 providing pull boxes, elbows, T's, and outlets for the passage through and emergence of electrical wires carried by the conduit systems.

20 The primary object of the invention is to provide an adapter which may be associated with any of the fittings above identified in a manner whereby different sized switches, lamp sockets and the like may be applied to 25 the fittings.

Another object of the invention is to provide a simple and cheap construction of adapter as well as one which may be applied to the fitting in a convenient manner.

30 Further objects will appear upon reference to the accompanying drawing and the following detailed description, the points of novelty being particularly pointed out in the subjoined claims.

35 In said drawing:—

Figure 1 is a side elevation of a fitting, partly in section and illustrating the application of the invention when associated with a snap switch of the ten ampere size;

40 Fig. 2 is a sectional view on the line 2—2 Fig. 1;

Fig. 3 is a top plan view of the fitting illustrated in Figs. 1 and 2 with the switch removed and illustrating the application of 45 the adapter;

Fig. 4 is a top plan view illustrating the application of the adapter to a different design of fitting, such as an elbow;

Fig. 5 is a side elevation partly in section 50 illustrating the application of an annular ring as used in the form of adapter shown in Figs. 1 to 4 inclusive;

Fig. 6 is a top plan view of the ring which is employed in connection with the adapter 55 when it is used to accommodate the size of switch illustrated in Fig. 5;

Fig. 7 is a side elevation partly in section of a modified form of the adapter and illustrating the same as accommodating a five ampere snap switch;

Fig. 8 is a top plan view with the switch removed and illustrating the type of adapter shown in Fig. 7;

Fig. 9 is an enlarged detail view of one of the attaching lugs used in connection 65 with the type of adapter illustrated in Figs. 7 and 8;

Fig. 10 is a side elevation illustrating the adapter as accommodating a lamp socket;

Fig. 11 is a side elevation illustrating the 70 adapter as accommodating a ceiling receptacle; and

Fig. 12 is an enlarged detail view of the adapter.

Referring to the drawings in detail particularly to that form of adapter illustrated in Figs. 1 to 3 inclusive, 1 represents a fitting having one of its ends closed and the other end provided with threaded openings adapting it to receive the conduit, its face 80 being opened providing for the outlet or emergence of the wires. As heretofore practised, this opening is usually covered by a plate or other device. To render this possible a pair of lugs 2 project inwardly of the 85 opening having screw-threaded holes which are made to receive screws in securing the plate or other device over the opening. It is proposed by the present invention to employ this plate attaching means as a medium for 90 securing an adapter plate such as 3 over the opening. This adapter plate 3 is constructed of a dimension to overlie the opening in the face of the fitting, but with outwardly projecting sides which are provided 95 with recessed portions 4 which are made to receive the ends of small bolts 5, the heads of which being seated in openings in the porcelain base of the appliance which is attached to the fitting, in the present instance, 100 shown as a ten ampere snap switch. To securely fix the switch to the plate 3, nuts 6 are employed under the plate 3 for engaging the screw-threaded ends of the bolts 5, thus enabling the base of the switch to be securely 105 clamped to the plate. That part of the plate 3 which overlies the opening in the base of the fitting is also provided with an elongated opening 7 which enables the wires to be passed from the fitting and attached to the binding posts of the appliance.

It is to be noted that the openings 4 in the

extensions of the plate 3 enable the adapter to accommodate appliances even though the openings in the porcelain base thereof which receive the bolts 5 should not conform in spaced relation in every switch.

With reference to Fig. 4, the construction just described with reference to Figs. 1 to 3, inclusive, is identical, this figure merely showing a different type of fitting, such fitting being of what is known in the trade as an elbow type.

Referring now to Figs. 5 and 6, this form of the invention is substantially the same as that illustrated in the previously described figures with the exception that an annular ring 8 is employed for supporting the switch above the adapter plate 3. This ring conforms in dimensions to the porcelain base of the switch and is provided with an annular recessed portion 9 for receiving the base of the switch.

With reference to that form of the invention illustrated in Figs. 7 to 10 inclusive, the adapter plate is shown as a ring piece 10 rendering it applicable for attaching size five ampere switches and other small variety of appliances. This form also illustrates a somewhat different means for attaching the appliance to the adapter plate. However, it is secured to the opening in the base of the fitting in the same manner as in the figures above referred to. Referring specifically to the ring piece, this is constructed of any suitable material having a base or flange with openings on opposite sides thereof which openings are made to receive small bolts or screws 11 which pass through the openings and engage the slots 4 in the adapter plate. Instead of employing nuts 6 as in the other form a pair of ears or lugs 12 are employed, these lugs or ears having a screw-threaded opening which is made to receive the screw-threaded end of the bolts or screws 11 and with upturned ends 13 which engage the edges of the adapter plate and the ring piece 10, thus enabling the ring piece to be securely fixed to the adapter plate. The ring piece 10 is also constructed with an inner raised portion 14 providing a supporting base for the switch or appliance. The inner circumference of the raised portion 14 is open and registers with the opening 7 in the adapter plate 3, thus enabling the wires to be projected from the fitting to the binding post of the appliance. The means for securing the appliance to the supporting base of the ring piece 10 comprises inwardly projecting portions 15 having slotted openings 16 which are made to receive small bolts 17 which are carried by the appliance, nuts 18 being used to engage the screw-threaded ends of the bolts thus clamping the appliance securely to its supporting base.

Referring to Figs. 11 and 12 wherein is shown the ceiling receptacle as applied to the fitting, the attachment of this appliance may be effected in a manner such as proposed with the ten ampere switch, that is to say, it is of such size as will enable it to be secured directly to the adapter plate 3.

While the above description makes mention of only five and ten ampere sized switches, it is of course understood, that even a larger variety of switches and appliances may be attached to the adapter plates as the slotted openings make ample provision for receiving the securing bolts of the appliance regardless of their spaced relation.

I claim:

1. In a conduit fitting, the combination of an adapter for accommodating the fitting to electrical appliances having different size base dimensions, said adapter comprising a plate adapted to engage the fitting, an opening in the plate registering with the opening in the fitting, an extension on each side of the plate projecting beyond the sides of the fitting, and an elongated opening in each extension adapted to receive the base securing bolts of the electrical appliance.

2. In a conduit fitting, the combination of an adapter for accommodating the fitting to electrical appliances having different sized base dimensions, said adapter comprising a plate adapted to engage the fitting, an opening in the plate registering with the opening in the fitting, an extension on each side of the plate projecting beyond the sides of the fitting, and elongated means on said plate for attaching the electrical appliance.

3. In a conduit fitting, the combination of an adapter for accommodating the fitting to electrical appliances having different size base dimensions, said adapter comprising a plate adapted to engage the fitting, an opening in the plate registering with the opening in the fitting, an extension on each side of the plate projecting beyond the sides of the fitting, and means on said plate for attaching the electrical appliance.

4. In a conduit fitting, the combination of an adapter for accommodating the fitting to electrical appliances having different sized base dimensions, said adapter comprising a plate adapted to engage the fitting, an opening in the plate registering with the opening in the fitting, an extension on each side of the plate projecting beyond the sides of the fitting, and elongated openings on said extensions for attaching the electrical appliance.

The foregoing specification signed at Scranton, Penna., this 1st day of March, 1918.

WILLIAM A. HARVEY.
